UNITED STATES PATENT OFFICE.

ARTHUR T. RUTHVEN, OF TOPEKA, KANSAS.

CARBURETER

1,049,273.

Specification of Letters Patent. Patented Dec. 31, 1912.

Application filed January 9, 1912. Serial No. 670,145.

To all whom it may concern:

Be it known that I, ARTHUR T. RUTHVEN, a citizen of the United States, residing at Topeka, in the county of Shawnee and State of Kansas, have invented certain new and useful Improvements in Carbureters, of which the following is a specification.

My invention relates to carbureters, and my object is to provide a simple and efficient apparatus of this character which may be employed to advantage in supplying gaseous fuel to the motors of automobiles, to the end that the carbureters now in general use for that purpose may be dispensed with.

By employing my apparatus, an adequate amount of fuel of uniform richness is always insured; and in order that the invention may be fully understood, reference will now be made to the accompanying drawing, in which:

Figure 1 is a sectional view of a supply tank provided with my apparatus. Fig. 2 is a perspective of a float, forming an important feature of the invention. Fig. 3 is a cross section of the float, on line III—III of Fig. 1. Fig. 4 is a perspective of a wick, a plurality of which are employed in carrying out the invention.

1 designates a supply-tank for holding gasolene or other hydrocarbon oil to be converted into gaseous fuel. Said tank is provided with an inlet 2, through which it may be supplied, said inlet being normally closed by a removable cap 3.

4 designates the float, forming one of the important features of the invention. Said float embodies a receiving-chamber 5, a discharge chamber 6, two air-chambers 7, and a wick-chamber 8. The receiving-chamber 5 is located at one end of the float, and the discharge-chamber 6, is located at the opposite end of said float, while the wick-chamber 8 extends throughout the length of the float between the two air-chambers 7. The receiving-chamber 5 is provided at its upper side with a nipple 9, having a hose connection 10, which hose is connected at its upper end to an inlet-pipe 11, extending through the adjacent end of tank 1, and provided with an air-receiving funnel 12, having a strainer 13 to intercept dust or other foreign matter which might otherwise enter said funnel with the air. The inlet pipe 11 is provided with a check-valve 14, adapted to open toward the hose 10 when

the apparatus is in operation. The air entering the receiving-chamber 5 is permitted to flow outward therefrom into the wick-chamber 8 through a horizontal row of inlet-ports 15, in the vertical rear wall of said chambers. The discharge-chamber 6 communicates with the wick-chamber 8 through a horizontal row of inlet ports 16, in the vertical front wall of said chamber 6. The upper portion of the discharge-chamber 6 is provided with a nipple 17, having a hose-connection 18, communicating with an outlet-pipe 19, leading to the motor or other point of use, not shown. Back-pressure from the outlet-pipe 19 to the discharge-chamber 6 is prevented by a check-valve 20, communicating with said outlet-pipe. Outlet-pipe 19 is provided with an air-intake 21, provided with a valve 22 to control the flow of air therethrough.

23 designates a plurality of wicks consisting of any suitable absorbent material, each wick being stretched on a suitable frame 24. Frames 24 are placed side by side in the wick-chamber 8 as shown in Figs. 1 and 2, and are supported in said wick-chamber by a pair of flanges 25, removably secured to the bottoms of the air-chambers 7 by screws 26.

In practice, when the apparatus is connected to a motor, air is intermittently drawn through the apparatus by the action of said motor. As the air passes through the wicks 23, it generates into fuel, the oil drawn to the upper portions of said wicks by capillary attraction, and entering the discharge chamber 6 through ports 16, passes outward through hose 18 and the outlet-pipe 19 to the motor. As the rich hydrocarbon fuel passes through the outlet pipe 19, it is mixed with air taken through the intake 21, the amount of air being regulated by the valve 22, which in turn may be regulated from a point adjacent the seat of an automobile when the apparatus is installed on a vehicle of that character. The air-chambers 7 are, preferably, so proportioned as to support the upper half of the float above the level of the oil in tank 1, so that it will not obstruct the passage of the air through the upper portion of the wick-chamber, and at the same time, seal the air from passing from said wick-chamber into the tank 1.

Although the float is free to move up and down with the level of the oil within tank

1, it fits the interior of said tank sufficiently close to prevent damage thereto incident to any lateral or longitudinal movement which may be imparted to said generator by an automobile, containing the same, traveling over the uneven surface of a roadway.

While I have shown and described the preferred construction of my apparatus, I do not wish to be confined to the exact details of construction illustrated by the drawing, but reserve the right to make such changes as properly fall within the spirit and scope of the appended claims.

Having thus described my invention what I claim and desire to secure by Letters Patent, is:

1. In combination with a tank, a float therein composed of a pair of spaced transverse receiving and discharging chambers located at opposite ends of the tank and a pair of spaced longitudinal side air chambers that are connected to the ends of the receiving and discharging chambers, flanges carried by the bottoms of the air chambers and extending inwardly to project in the space between said air chambers, wick frames having their bottoms seating on said flanges and located between the inner side faces of the air chambers, the inner walls of the receiving and discharging chambers being formed with openings, an air inlet in the tank, an outlet, and flexible hose connections between the inlet and the re-

ceiving chamber and between the outlet and the discharging chamber.

2. In combination with a tank, a float therein composed of a pair of spaced transverse receiving and discharging chambers located at opposite ends of the tank, and a pair of spaced longitudinal side air chambers that are secured to the ends of the receiving and discharging chambers, the inner walls of the receiving and discharging chambers being formed with a series of openings which face each other and are located intermediate the tops and bottoms of said inner walls to provide a direct horizontal passage through the space defined by the float, which openings directly communicate with the space between said chambers, a series of wicks supported by the float and located in said space, a flexible pipe directly connected at one end to the receiving chamber and at its opposite end to the tank for supplying air to the interior of the receiving chamber and a flexible pipe directly connected at one end to the discharging chamber and at its opposite end to the tank for exhausting the fuel from the discharging chamber.

In testimony whereof I affix my signature, in the presence of two witnesses.

ARTHUR T. RUTHVEN.
